(57) **CLAIM**

The ornamental design for a seat with armrests of a truck vehicle, as shown and described.

DESCRIPTION

FIG. 1 is a right, front perspective view of a seat of a truck showing my new design, said seat having the armrests rotated to a down position;

FIG. 2 is a right, front perspective view of a seat of a truck showing my new design, said seat having the armrests rotated to an up position;

FIG. 3 is a right view of a seat of a truck showing my new design, said seat having the armrests rotated to a down position;

FIG. 4 is a right view of a seat of a truck showing my new design, said seat having the armrests rotated to an up position;

FIG. 5 is a front view of a seat of a truck showing my new design, said seat having the armrests rotated to a down position;

FIG. 6 is a front view of a seat of a truck showing my new design, said seat having the armrests rotated to an up position;

FIG. 7 is a top down view of a seat of a truck showing my new design, said seat having the armrests rotated to a down position;

FIG. 8 is a top down view of a seat of a truck showing my new design, said seat having the armrests rotated to an up position;

FIG. 9 is a rear view of a seat of a truck showing my new design, said seat having the armrests rotated to a down position; and,

FIG. 10 is a rear view of a seat of a truck showing my new design, said seat having the armrests rotated to an up position.
